UNITED STATES PATENT OFFICE.

HORATIO G. CRESS, OF TROY, OHIO. ASSIGNOR TO THE H. G. CRESS COMPANY, OF TROY, OHIO, A CORPORATION OF OHIO.

EDUCATIONAL DEVICE.

Application filed June 14, 1924. Serial No. 719,956.

To all whom it may concern:

Be it known that I, HORATIO G. CRESS, a citizen of the United States, residing at Troy, in the county of Miami and State of 5 Ohio, have invented certain new and useful Improvements in Educational Devices, of which the following is a specification, reference being had therein to the accompanying drawing.

10 This invention relates to improvements in education devices.

It is the object of the present invention to provide a movable button for an educational device which will be easily moved 15 to the desired position and at the same time prevented from turning around when so positioned; and which will have a shank scarcely visible at its edges when the button is in use, thereby adding to the attractiveness 20 of the device.

Devices of this character consist of a support having passageways and a set of movable buttons adapted to be positioned in various order therein, such as a storage passageway and a transverse passageway or passageways connecting with the storage passageway. These buttons may have on them 25 the letters of the alphabet so that words may be composed by selecting the proper buttons from the storage passageway and shifting the set until the desired button comes opposite the transverse passageway and then moving it into said transverse passageway, or they may have on them numerals, animals or any desired design.

My present invention provides a very perfect button for this purpose, such button having two heads with their edges chamfered and a relatively narrow shank with 40 its edges curved and of such length that it will not allow the button to turn around in the passageways except at the junction of the same, said shank being cut-away at its edges so that it is practically invisible when the button is in use.

In the accompanying drawings:

Figure 1 is a plan view of an educational device in which my improved button is used;

50 Figure 2 is a sectional view taken on the line 2-2 of Figure 1;

Figure 3 is a side elevation of the button.

55 Figure 4 is a perspective view with the shank in section and one of the button heads removed;

Figure 5 is a plan view of a portion of the support and a horizontal section through the shank of one of the buttons, the lower head of the button shown in plan; and

Figure 6 is a vertical sectional view of 60 several buttons and a modified form of support having a double face.

In these drawings 1 indicates an elliptical shaped member of paste board or similar material having a passageway 2 conforming 65 to the contour thereof. It will be understood that the member 1 or support may be of any desired configuration and that there may be any number of transverse passageways. The passageway 2 is adapted to receive double head buttons 3 having their under edges chamfered as shown at 4, and adapted to contain figures, objects, or letters of the alphabet, in the present instance, the latter, and serves what may be termed 70 75 as a storage passageway. A separate passageway 5 leads from the passageway 2 and is designed as a working passageway in which the desired characters may be moved in proper order. It will therefore be understood that the supply of characters is never more than may be accommodated by the storage passageway 2. In the form of device shown in Figures 1 and 2 when the buttons 3 have been placed in the passageway 2 the member 1 is inserted in a box-like structure having sides 6 and a bottom 7. In practice it has been found that it is difficult to keep the supports or members 1 perfectly true and that one edge of the buttons 80 85 will tend to drop down when being moved from one passageway to another and in the case of buttons having straight under edges they will catch on the support and necessitate being lifted so that the entire head will 90 95 rest on the support. By chamfering the under edges of the button heads it has been found that they will readily move from one passageway to another and thus overcome the annoyance heretofore experienced with 100 the old form of button.

In devices of this kind it is decidedly advantageous to have buttons that will not permit of their being turned around in the passageways and at the same time it is desirable to have buttons whose shanks will be substantially invisible when the buttons are mounted in the support. To this end I have provided the present form of double head button having a comparatively thin 110

shank 8, cut-away at its edges as shown at 9. It will be observed that the edges of the shank are curved, preferably from the center of the button, to facilitate moving 5 the button from one passageway to the other, as clearly shown in Figure 5. In this figure I have illustrated a button about to be moved from the storage passageway to the working passageway, in which position 10 the curved edges of the shank are contacting with the edges of the passageways whereby the button will be more easily moved. The length of one axis of the shank 7 is such with respect to the length of the other that the button is prevented from 15 turning around in the passageways.

Referring to Figure 6, I have shown a modified form of support in which both faces are finished off for use in connection 20 with both heads of the buttons. When using supports of this type the buttons will carry letters, numerals, or designs on both heads. In this form the support comprises two finished faces 10 and 11 so that when 25 it is supplied with buttons of the type just referred to, it will serve the purpose of two devices. For instance, by having buttons with the alphabet on one head and figures on the other head, the one board 30 may be utilized both to teach the child to spell and add.

The button herein described, not only provides an easily operated button for use

in educational devices for children, but it is susceptible of being made very cheaply. 35 The curved edges of the shank and the chamfered edges of the heads can be formed at the time and by the means employed to form the general body of the device, as by a cutting tool when the stock 40 is in a cutting lathe.

Having thus fully described my invention, what I claim as new and desire to secure by Letters Patent, is:—

1. A button for an educational device 45 consisting of two heads chamfered from their edges to a shank, and a relatively thin connecting shank cutaway at the edges to render the same substantially invisible when the button is mounted in the support. 50

2. In a device of the character described, the combination with a member having a storage passageway and a working passageway communicating therewith, of a plurality of buttons each consisting of two 55 heads having their edges chamfered, the chamfer extending from the edges of said heads to a shank, and a relatively thin connecting shank cut-away at the edges to render the same substantially invisible when 60 the button is mounted in the support and yet prevent the same from turning when so mounted.

In testimony whereof, I affix my signature.

HORATIO G. CRESS.
